Patented Sept. 10, 1895.

UNITED STATES PATENT OFFICE.

TAYLER BALLEW, OF ARLINGTON, MISSOURI.

STEAM-ENGINE.

SPECIFICATION forming part of Letters Patent No. 546,266, dated September 10, 1895.

Application filed June 20, 1895. Serial No. 553,480. (No model.)

To all whom it may concern:

Be it known that I, TAYLER BALLEW, a citizen of the United States, residing at Arlington, in the county of Phelps and State of Missouri, have invented a new and useful 5 Steam-Engine, of which the following is a specification.

The primary object of the present invention is to secure a quick responsive action of the 10 piston when the steam is cut off and the said piston is beginning the return stroke.

Another object, and of vital consequence, is to obviate pounding or working of the piston against live steam, which frequently results 15 in the blowing out of the cylinder-head and working great damage to the machinery and contiguous structures, and not unfrequently causing loss of life and limb. By the present invention live steam can be admitted 20 at one end of the cylinder only. Hence the disastrous results attendant upon the construction of engines in which it is possible to admit the live steam at both ends of the cylinder at the same instant are wholly avoided.

25 A still further purpose of the invention is to dispense with the ordinary steam-chest and locate it and the cut-off within the cylinder, as will be more fully set forth hereinafter.

The improvement consists, essentially, of 30 the novel features and the peculiar construction and combination of the parts, which hereinafter will be more fully set forth and claimed, and which are shown in the accompanying drawings, in which—

35 Figure 1 is a perspective view of a steam-engine embodying the vital principles of the invention. Fig. 2 is a longitudinal section of the cylinder, showing the relative disposition of the parts when the piston is at the end of 40 its stroke in one direction. Fig. 3 is a view similar to Fig. 2, showing the relative location of the parts when the piston is at the end of its stroke in the opposite direction. Fig. 4 is a cross-section of the cylinder on the line X 45 X of Fig. 2. Fig. 5 is a detail view of the piston. Fig. 6 is a detail view of the cut-off valve.

In general appearance the steam-engine is 50 not unlike an engine of ordinary construction, and comprises a steam-cylinder 1, mounted upon a bed 2, slotted ways 3 for the cross-head 4 to travel in, and which has connection

with the piston 5 by means of the rod 6, the shaft 7 having a crank 8 at one end connected by a pitman 9 with the cross-head 4, and an 55 eccentric 10, connected in the usual manner by a rod 11 with a valve 12, whereby the exhaust-ports from the cylinder 1 are controlled, and a band-pully 13 mounted upon the shaft 7, from which the power is taken by means 60 of a belt in the ordinary way.

The steam-cylinder 1 has a centrally-disposed live-steam port 14, which has connection by means of a pipe 15 with a steam-generator in a manner well understood in the art 65 of steam-engineering, and is provided with exhaust-ports 16, which lead from the ends of the cylinder to an exhaust-pipe 17, by means of which the exhaust-steam is conveyed to a suitable point of discharge. The valve 12 is 70 located at the junction of the exhaust-ports 16 with the exhaust-pipe 17, and has oppositely-disposed passages 18 to establish communication between the exhaust-ports and the exhaust-pipe 17. These passages 18 are so 75 related that only one exhaust-port at a time will be in communication with the exhaust-pipe, the other exhaust-port being closed. The valve-stem 19 has connection with the rod 11, whereby the valve is actuated to open and 80 close the exhaust-ports at the proper time to effect a reverse movement of the piston. The exhaust-ports are formed in a thickened part 20 of the steam-cylinder, which part is located on the under side so as to be hidden 85 from view and not detract from the symmetrical appearance of the upper portion of the engine-cylinder. The valve 12 is likewise seated in this thickened part 20. In order to secure the cylinder upon its bed, it is formed 90 with lateral flanges 21, which are apertured to receive the bolts or fastenings by means of which the said cylinder is held upon its bed. One of the flanges has a slot 22 for the passage of the valve-stem 19. 95

The piston 5 has connection with its operating-rod 6 in any preferred manner, and is double-ended, being provided with two heads 23 and 24, which are suitably packed to obtain a steam-tight joint between them and the cylinder, and which are connected by an approximately cylindrical casing 25, which is formed in its sides at opposite points with openings 26 for the ingress of live steam into

the casing 25. A steam-passage 27 extends through the piston-head 23 and communicates with one end of the casing 25, and a corresponding passage 28 is formed in the piston-head 24 and communicates with the opposite end of the said casing, and these passages admit of the live steam entering the ends of the steam-cylinder 1 from the casing 25 in the efficient working of the engine. In order that one passage may be closed while the other is opened, a cut-off valve 29 is provided and located within the casing 25, and consists of a stem 30 having heads 31, which are adapted to fit against the inner sides of the casing-heads and close the said passages. This cut-off valve is of less length than the distance between the heads of the casing, so that it has a limited longitudinal movement, thereby enabling it to close only one passage at a time.

2c The operation of the engine may be briefly stated as follows: The live steam entering through the port 14 is confined between the piston-heads 23 and 24 and passes into the casing 25 through the openings 26, and the 25 valve 12 being turned so as to establish communication between the exhaust-port 16 and the pipe 17 at the left-hand end of the steam-cylinder the live steam will pass from the casing 25 through the passage 28 into the 30 right-hand end of the steam-cylinder and drive the piston from the right-hand end of the said cylinder to the left-hand end thereof. As the piston reaches the limit of its stroke to the left, the position of the valve 12 will be 35 changed by means of its actuating mechanism, as hereinbefore stated, and the exhaust-port previously opened will be closed and the one closed opened, which will result in a quick movement of the cut-off valve so as to 40 close the passage 28 and open the passage 27, thereby permitting the live steam which previously escaped through the passage 28 to find its way through the passage 27 and into the left-hand end of the cylinder, thereby 45 driving the piston to the right. The operation just described is repeated at each stroke of the piston, the valves 12 and 29 reversing and causing the piston to be driven in an opposite direction to its previous stroke. It 50 will be seen that the instant the valve 12 is reversed the cut-off valve 29 will fly toward that end of the cylinder whose exhaust-port is open, thereby shutting off the supply of live steam to this end of the cylinder and admitting it to the opposite end. Inasmuch as 55 the exhaust-port at one end of the cylinder is always open while the opposite exhaust-port is closed, it will be readily comprehended that no pounding action can possibly take 60 place and that the live steam must find its way to that end of the cylinder whose exhaust-port is closed, thereby driving the piston in the proper direction. The cut-off valve will at all times shut off the supply of live steam 65 to that end of the steam-cylinder whose exhaust-port is open. Hence there can be no possible waste of steam in the operation of

the engine. It will be seen that the instant the steam is shut off from the engine a vacuum is created in each end of the cylinder which 70 checks the movement of the piston and has the same effect as applying a brake to the engine. While the cut-off is shown located within the casing comprised between the two piston-heads, it is obvious that it can be applied to a steam-chest provided exterior to the cylinder, and that the two piston-heads 23 and 24 can be merged or consolidated into a single piston.

The invention is applicable to the various 80 styles and patterns of engines which embody in their construction a cylinder and a reciprocating piston. Therefore it must be understood that in adapting the same to meet the various demands changes in the form, proportion, and the minor details of construction may be resorted to without departing from the principle or sacrificing any of the advantages of this invention.

Having thus described the invention, what 90 is claimed as new is—

1. An engine comprising a cylinder having a centrally-disposed ingress port and end exhaust ports, a reciprocating piston within the cylinder comprising heads which have passages therethrough and which inclose a space which is in communication with the ingress port, and a cut-off valve adapted to operate between the piston heads and close the passages therein, substantially as described for the purpose set forth.

2. An engine comprising a cylinder having a centrally-disposed ingress port and having end exhaust ports, a piston adapted to operate in the cylinder and provided with two heads which are located a distance apart and inclose a space which is in communication with the said ingress port, said heads having passages therethrough and connected by a casing, and a cut-off valve adapted to operate in the said casing to close the passages in the piston heads, substantially as described for the purpose set forth.

3. An engine comprising a cylinder having a centrally-disposed ingress port and having end exhaust ports, means for controlling the said exhaust ports, a piston adapted to operate in the cylinder and comprising two heads which are provided with passages, and which inclose a space that is in communication with the ingress port, and a cut-off valve adapted to operate between the piston heads and close the passages therethrough, substantially as described for the purpose set forth.

4. The combination with a cylinder having a centrally-disposed ingress port and end exhaust ports, a valve for controlling the said exhaust ports and actuating mechanism therefor, of a piston comprising two heads located a distance apart and inclosing a space which is in communication with the said ingress port, and which have passages therethrough, a casing connecting the piston heads and having openings in its sides, and a cut-off valve

adapted to operate in the said casing and close the passages in the piston heads, substantially as set forth.

5. An engine comprising a cylinder having a centrally-disposed ingress port and having lateral flanges by means of which it is secured upon its bed, and having the lower portion thickened and provided with exhaust passages which communicate with the opposite ends of the cylinder and with an exhaust pipe, a valve at the junction of the exhaust passages and adapted to establish communication with one of the said exhaust passages and the exhaust pipe at a time, said valve being mounted in the thickened portion of the cylinder, a piston

located in the cylinder and comprising two heads which inclose a space in communication with the ingress port, and which have passages therethrough, a casing connecting the piston heads and having openings in its sides, and a cut-off valve adapted to operate in the casing, substantially as described for the purpose set forth.

In testimony that I claim the foregoing as my own I have hereto affixed my signature in the presence of two witnesses.

TAYLER BALLEW.
